[57] CLAIM

The ornamental design for a display rack for candles,
substantially as shown and described.

DESCRIPTION

FIG. 1 is a perspective view of a display rack for candles showing my new design.

FIG. 2 is a top plan view thereof.

FIG. 3 is a front elevational view as seen from the bottom side of FIG. 2.

FIG. 4 is a side elevational view as seen from the left side of FIG. 2, the opposite side being a mirror image thereof; and

FIG. 5 is a perspective view shown broken away to indicate indeterminate length.

The rear of the display rack for candles is substantially flat and unornamented. The open bottom of the display rack is conventional for the configuration shown.
